Frederick L. Duer, Western Springs, and Joseph J. Orlof, Wheaton, Ill., assignors to Duer Tube Bending Company, Inc., Bellwood, Ill.

Continuation-in-part of abandoned design application Ser. No. 439,378, Feb. 4, 1974. This application Feb. 26, 1975, Ser. No. 552,973

Term of patent 14 years

Int. Cl. D12—16

U.S. Cl. D12—157

FIG. 1 is a perspective view of an automotive luggage carrier showing our new design, it being understood that the broken line shown of the automobile roof is for illustrative purposes only; and

FIG. 2 is a side elevational view of FIG. 1.

This is a continuation-in-part of design application Ser. No. 439,378, filed Feb. 4, 1974, and now abandoned.

We claim:

The ornamental design for an automotive luggage carrier, substantially as shown and described.
